UNITED STATES PATENT OFFICE.

NATHANIEL S. MONROE AND ANDREW J. MONROE, OF ARTHUR, ILLINOIS.

ROAD-WORKING MACHINE.

1,397,011.

Specification of Letters Patent. Patented Nov. 15, 1921.

Application filed July 19, 1919. Serial No. 311,926.

To all whom it may concern:

Be it known that we, NATHANIEL S. MONROE and ANDREW J. MONROE, citizens of the United States, residing at Arthur, in the county of Douglas and State of Illinois, have invented certain new and useful Improvements in Road-Working Machines, of which the following is a specification.

This invention relates to improvements in road working machines and particularly to machines of that class which are provided with rearwardly convergent scraper bars spaced apart at their rear ends to permit the passage therebetween of a portion of the surface dirt which is taken from the road by the action of the scraper bars and moved in the direction of the middle of the road where it is packed and smoothed to form a crown. Types of this class of machines are shown in Letters Patent of the United States No. 1,131,409, issued to Nathaniel S. Monroe on March 9, 1915, and also in Letters Patent No. 1,133,876 issued to Nathaniel S. Monroe on March 30, 1915, and in Letters Patent No. 1,247,135, issued to Nathaniel S. Monroe, George W. Monroe and Andrew J. Monroe, November 20, 1917, and in the pending application of Nathaniel S. Monroe, Serial No. 824,163, filed March 12, 1914.

In machines of this type the scraper bars are extremely heavy and it has been found to be difficult to control the spread of these bars and to rapidly collapse them when it is necessary to do so to avoid obstructions, or to enable the machine to pass over comparatively narrow bridges, and in emergencies.

One object of the present invention is to effect improvements whereby the scraper bars can be perfectly controlled and adjusted as may be required, by one operative stationed on the machine, and without great manual exertion on his part and without the necessity of stopping the machine, and also by utilizing the forward movement of the machine so that the front ends of the scraper bars are lifted clear of the road surface, by the forward movement of the machine and by the swinging movement of the cranes occasioned thereby, and without the necessity of manually or otherwise operating the hoisting tackles which connect the scraper bars to the cranes, and thus causing the scraper bars to be collapsed or retracted in a very short space of time and by a very slight forward movement of the machine.

In machines of this type, it has been found

that the rear axles, because of the great stresses to which they are subjected are liable to be sprung or slightly thrown out of alinement and to hence cause the rear wheels to also get out of line, and another object of my invention is to effect improvements in the construction of the rear axle so that the same forms also the rear cross bar of the main frame and is provided with means whereby the portion on which the rear wheels are mounted may be adjusted as may be required to preserve alinement and to cause the rear wheels to track with the front wheels or run exactly parallel therewith, and to also greatly strengthen the construction of the rear axle and enable any part thereof which may possibly get out of repair to be removed and replaced by a new part.

With the above and other objects in view, the invention consists in the construction, combination and arrangement of devices hereinafter described and claimed.

In the accompanying drawings:

Figure 1 is a plan of a road working machine constructed in accordance with our invention and showing the scraper bars with their front ends spread apart as when the machine is in operation.

Fig. 2 is a side elevation of the same.

Fig. 3 is a diagrammatic plan showing the scraper bars in spread, operative position in full lines and in collapsed or retracted position in dotted lines.

Fig. 4 is a diagrammatic elevation also showing the scraper bars in such positions.

Fig. 5 is a diagrammatic transverse sectional view on the plane indicated by the line 5—5 of Fig. 3, and showing the scraper bars in spread position in full lines and in retracted or collapsed position in dotted lines.

Fig. 6 is a detail elevation of one of the tackle operating means and its spring brake for preventing casual movement thereof.

Fig. 7 is a detail elevation partly in section, of the rear end of the main frame and showing the construction of the rear axle and its adjusting and strengthening means.

Fig. 8 is a detail plan of the same, partly in horizontal section.

Fig. 9 is a detail rear elevation of the same.

The main frame 1 of our improved road working machine is provided with rearwardly diverging side bars 2, of channel iron and are connected together at their

front ends by a cross bar 3 the ends of which are here shown as projecting outwardly therefrom. Intermediate cross bars 4, 5 and 6 are also here shown. The rear cross bar or beam 7 of the main frame is an I-beam the ends of which are riveted or bolted to the side bars 2 and arranged in the opposing channeled sides thereof and said bar 7 also forms the arch bar of the rear axle. Axle arms or blocks 8, which in practice are short sections of I-beams are arranged with their inner portions under the beam or arch bar 7 and with their upper flanges bolted or riveted to the base flanges of the bars 2 and 7 as shown at 9, the outer portions of said arms or blocks projecting outwardly beyond the sides of the main frame as shown. The rear axle members 10, the outer portions of which form the spindles 15 on which the rear wheels 11 are mounted, are arranged under the blocks or arms 8 and have their inner ends bolted thereto as at 12. Saddle blocks 13 are secured by bolts 14 to the under side of the outer portions 20 of the arms 8, the said bolts passing through the base flanges of said arms. Each of the said saddle blocks has an opening 15 through which the axle member 10 passes. Braces 16 are arranged under the rear portions 25 of the bars 2 and have their front ends bolted thereto as at 17, the rear ends of said braces extending between the lower sides of the arms 8 and the upper sides of the axle members 10 and being bolted or riveted to the base flanges of said arms 8 as at 18. Bracket blocks 19 are riveted or bolted to the outer sides of the bars 2 and are provided with openings through which extend the front portions of rearwardly diverging 30 brace and adjusting rods 20 the rear portions of which extend through openings in the saddle blocks 13. At their front ends the said rods are provided with nuts or heads 21. Adjusting nuts 22 are threaded on the rear portions 35 of said rods and are arranged on the front and rear sides of the saddle blocks, wedge-shaped spacer blocks or washers 23 being arranged between said nuts and the front and rear sides of the saddle blocks 50 as shown in Figs. 7 and 8. This construction of the rear axle makes the same exceedingly strong, also enables the same to be readily and cheaply repaired in case of injury from any cause to any part thereof, 55 and also enables the members 10 to be adjusted, by merely appropriately turning the nuts 22 by means of a wrench, to keep said members 10 in alinement and to cause the rear wheels to properly track, under all conditions, and run exactly parallel with the front wheels.

The front truck 24 is here shown as comprising an arched axle 25, front wheels 26, a draw bar 27, for attachment to a tractor 60 and braces 28 for said axle and draw bar.

A suitable platform 29 is provided on the front portion of the frame 1, with a top 30, and a tool box 31 is also in practice provided. We would have it understood that while we here show and describe a preferred construction of the main frame, the same may be of any suitable construction, without departing from the spirit of our invention and within the scope of the appended claims, and we do not desire to limit ourselves in this particular.

Our preferred construction of the main frame makes the same sufficiently strong to withstand the stresses occasioned by working conditions and the great weight of the scraper bars 32 and the weight and leverage of the drag 33.

A standard 34 rises from the center of the cross beam 7. A pair of rearwardly converging bars 35 have their front ends bolted on the arms 8 of the rear axle and their rear ends spaced apart and provided with upwardly and forwardly inclined standards 36, said bars 35 being inclined rearwardly and upwardly. Brace bars 37, which are similarly inclined, have their front ends bolted on the rear end of the frame and their rear ends bolted to the upper ends of said standards 36. Braces 38, which cooperate with the standard 34 to form trusses, have their front ends bolted on the cross bar 6 of the main frame, their intermediate portions secured to the upper end of the standard 34 and their rear ends secured to the lower ends of the standards 36 and rear ends of the arms 35. Rearwardly and upwardly inclined standards 39 are secured to the arms 35, standards 36 and braces 37, and a pulley 40 is mounted between the upper ends of said standards 39. The drag 33 105 may be of any suitable construction and is here shown as provided with longitudinally adjustable drag bars 41 the front ends of which are pivotally connected as at 42 to the rear portion of the main frame on opposite 110 sides thereof. A pulley 43 is connected to the drag and a suitable chain 44 or the like has one end secured to the standards 39, said chain passing around said pulley 43, and over the pulley 40 and its front end being 115 secured to a drum 45 which is mounted on the platform and is provided at one end with a hand wheel 46. Said drum is horizontally arranged and in practice a spring 120 brake 46a is provided for the hand wheel, 120 to prevent casual turning of the drum.

The scraper bars 32 are of the usual construction in machines of this class and their rear ends are pivotally connected, in appropriate spaced relation, to a link bar 47. 125 A draft chain 48 has its rear end connected by a bridle chain 49 to the link bar 47 and its front end connected to a vertically arranged drum 50 which is mounted under the platform as at 51. Said drum is provided 130

with a ratchet wheel 52 and trip dog 53 which the operator by his foot can readily disengage from the ratchet wheel, to quickly release the drum, and a shaft 54 extends upwardly from said drum and is provided with a hand wheel 55.

Spreader bars 56 have their front ends loosely pivotally connected as at 57 to the ends of the front cross bar 3 of the main frame and have their rear ends loosely pivotally connected as at 58 to the scraper bars at points a suitable distance from the front ends of the scraper bars. To enable the rear ends of the scraper bars to be raised and lowered, we provide a drum shaft 59 which is mounted on the main frame as shown and is connected by a hoisting chain 60 and a pulley 61 to the link bar 47, the rear end of said hoisting chain being secured to the rear ends of the arms 35 as at 62 and the front end of said chain being secured to said drum shaft for winding thereon and unwinding therefrom as at 63. The front end of said drum shaft has a beveled gear 64 which engages a similar gear 65 on a shaft 66. Said shaft is mounted in suitable bearings, is horizontally arranged, and is provided at one end with a hand wheel 67. A spring brake 68 engages said hand wheel to prevent casual turning of said shafts. Said spring brake is shown in detail in Fig. 6, and has a free end 69 to enable the operator, by stepping thereon, to cause said spring brake to release said hand wheel when this is desired. The said spring brake is of the same construction as the spring brake 48 hereinbefore mentioned and is similar to the spring brakes hereinafter mentioned in connection with the hand wheels of the hoisting means for the front ends of the scraper bars.

The said hoisting means comprises cranes 70, tackles 71, and drums 72. Each crane is here shown as comprising an upper member 73 or arm and a lower member 74, which are mounted for swinging movement in an inclined plane so that the outer end of each crane rises as it swings rearwardly. In effect the pivotal axis of each crane is rearwardly downwardly inclined as is indicated by the dotted line 75 a—a in Fig. 2, and as is also clearly indicated in Figs. 1, 3 and 4, and any suitable means may within the scope of our invention be employed for so mounting the cranes. As here shown, the inner end of each crane member 73 is mounted on one of the drums 72 and the inner end of the lower crane member is provided with a pivot pin 76 which may be placed in any of a series of openings 77 of a bracket 78 on one side of the main frame. Said openings 77 are eccentric to the drums 72 which form the pivots for the upper members of the cranes, and by shifting the pivot pins 76 the inclination of the pivot axes 75 a—a of the cranes 55 may be varied as may be desired, to cause

the front ends of the scraper bars to be lifted as high as may be desired from the road surface.

Each tackle 71 comprises a chain 79, a pulley 80 connected to one of the scraper bars 70 and its spreader bar, and a pulley 81 carried by one of the cranes, one end of each of said chains being secured to the crane, its opposite end being secured to one of the drums 72 and each of said chains engaging 75 the pulleys 80, 81, as shown. Each drum 72 has a beveled gear 82 at its upper end which is engaged by a beveled pinion 83 on a horizontal shaft 84. The said shafts are mounted in suitable bearings 85, above the platform and are provided at their inner ends with hand wheels 86, said hand wheels having spring brakes 87 which are identical in construction with the spring brakes 68 shown in Fig. 6. By means of the tackles, drums 85 and cranes, the front ends of the scraper bars may be manually raised and lowered and adjusted as may be required by the condition of the road and by the work, and the said tackles, cranes and drums prevent the front ends of the scraper bars from dropping, after the scraper bars have been thus adjusted or "set".

The scraper bars, which are drawn forwardly with the machine, by the draft chain 95 48 and its connections may be spread to any desired extent at their front ends, to operate on a road surface of any width and after the scraper bars have been manually adjusted at their front ends, as before described, it is not necessary to change such adjustment or for the operator to exert himself manually, nor is it necessary to employ any kind of motor or other power in order to retract or collapse the scraper bars while 100 the machine is moving forwardly, nor is it necessary to stop the machine nor to back it in order to accomplish such purpose. While the machine is moving forward and when for any reason it becomes necessary or desirable to collapse or retract the scraper bars all that it is necessary to do is for the operator, with one foot, to disengage the dog 53 from the ratchet wheel 52 and thereby release the drum 50. This slackens the draft 115 chain, the draft stress on the machine continues, and the load or work engaged by the scraper bars, that is to say, the dirt or soil or road material between the scraper bars tends by its resistance to bring the scraper 120 bars to a standstill. The cranes however, are free and owing to the fact that their pivotal axes 75 a—a are inclined, said cranes as they swing rearwardly under the stress exerted thereon by the hoisting tackles 71 125 move upwardly as is indicated in Fig. 5 and in the diagrams Figs. 3 and 4 and raise the front ends of the scraper bars while the rear ends of the scraper bars remain in contact with the ground and the spreader bars 56 130

draw the front ends of the scraper bars toward each other and thus collapse them. This movement of the cranes is automatic, is wholly incident to the forward movement 5 of the machine and the slackening of the draft chain 48, and does not require any operation whatever of the hoisting tackles. By thus automatically raising the front ends of the scraper bars, their front portions are 10 disengaged from the load of earth and they are free to rapidly and instantaneously swing inwardly and collapse, as will be understood.

Having thus described our invention, what 15 we claim is:—

1. In a road working machine, in combination with a main frame and carrying means therefor, a scraper bar, a spreader bar pivotally connected to the main frame and 20 the front portion of the scraper bar, hoisting means for the rear end of the scraper bar, a draft element connected to the rear portion of the scraper bar, means to releasably connect the draft element to the main 25 frame, a crane mounted on the main frame for swinging movement and having an inclined pivot axis so that the free end of said crane moves upwardly as the crane swings rearwardly, and connecting means between 30 the crane and the front portion of the scraper bar, said crane being swung rearwardly by the forward movement of the machine and hence caused to automatically raise the front end of the scraper bar, when 35 the rear end of the latter is released by the draft element and thus permitted to remain on the ground.

2. In a road working machine, in combination with a main frame and carrying 40 means therefor, a scraper bar, connecting means between the frame and the front portion of the scraper bar, a hoisting element connected to the front portion of the scraper bar, and mounted for rearward and upward 45 movement on the frame, by the forward movement of the machine, hoisting means for the rear end of the scraper bar, a draft element connected to the rear portion of the scraper bar, and means to releasably connect 50 said draft element to the frame.

3. In a road working machine, in combination with a main frame and carrying means therefor, a scraper bar, connecting means between the frame and the front portion 55 of the scraper bar, a hoisting element mounted for rearward and upward movement on the frame by the forward movement of the machine, a hoisting tackle carried by said element and connected to the

front portion of the scraper bar, means to operate and adjust said tackle, a draft element connected to the rear portion of the scraper bar, and means to releasably connect said draft element to the frame.

4. In a road working machine, in combination with a main frame and carrying means therefor, a scraper bar, a releasable draft connection between the frame and the rear portion of the scraper bar, a spreader connection between the frame and the front 70 portion of the scraper bar, and hoisting means mounted for rearward and upward movement on the frame and connected to the front portion of the scraper bar, to automatically raise the front end of the scraper 75 bar by the forward movement of the machine when the draft element is released.

5. In a road working machine, in combination with a main frame and carrying means therefor, a pair of scraper bars having their rear ends pivotally connected together in spaced relation, spreader bars connecting the frame to the front portions of the scraper bars, hoisting means for the rear ends of the scraper bars, a draft element releasably connecting the frame and the rear ends of the scraper bars, cranes mounted on the main frame for swinging movement and having inclined pivot axes so that the free ends of said cranes move upwardly as the 90 cranes swing rearwardly, hoisting and adjusting tackles for the front ends of the scraper bars and carried by the cranes, and operating and holding means for said tackles.

6. In a road working machine, a main frame including a pair of side bars, a connecting beam between the rear ends of said bars, axle arms secured under the ends of said beam, wheel carrying axle members 100 under and secured at their inner ends to said arms, saddle blocks also secured under said arms and through which said axle members extend, brace rods secured at their front ends to the sides of the frame and having 105 their rear portions extended through openings in the saddle blocks, and adjusting nuts threaded on the brace rods and bearing against the front and rear sides of the saddle blocks.

In testimony whereof we affix our signatures.
